MORTAR AND PESTLE

Melvin L. Johnsrud, 1244 S. 31st St., and John E. Koepke,
1328 S. 24th St., both of Manitowoc, Wis. 54220

Filed June 1, 1972, Ser. No. 258,922

Term of patent 14 years

Int. Cl. D28—01; D24—02

U.S. Cl. D16—1 R

FIG. 1 is a front elevational view of a mortar and pestle showing my new design;

FIG. 2 is a right side view of the mortar and pestle shown in FIG. 1;

FIG. 3 is a top plan view of the mortar and pestle shown in FIG. 1;

FIG. 4 is a bottom view of the mortar and pestle shown in FIG. 1; and

FIG. 5 is a cross-section taken on line 5—5 of FIG. 2.

We claim:

The ornamental design for a mortar and pestle, as shown.
